UNITED STATES PATENT OFFICE.

ROYAL E. DEANE, OF NEW YORK, N. Y.

IMPROVEMENT IN COOKING STOVES AND RANGES.

Specification forming part of Letters Patent No. 40,399, dated October 27, 1863.

To all whom it may concern:

Be it known that I, ROYAL E. DEANE, of the State, city, and county of New York, have invented certain new and useful Improvements in Cooking-Ranges; and I do hereby declare that the following is a full, clear, and exact description thereof, reference being had to the accompanying drawings, which form part of this specification, wherein—

Figure 1 is a top view of the range. Fig. 2 is a front elevation of the same. Fig. 3 is an interior end view showing the grate in section and the water-heater. Fig. 4 shows the grate in reverse position, (vertical.) Fig. 5 shows the same in same position, (horizontal,) as hereinafter further explained.

The letters and numbers of reference correspond in all the figures.

My said improvements relate to four principal features or functions of the cooking-range—viz., the adaptation of the fire to the purpose of baking, the adaptation of the fire to the purposes of broiling and roasting, the mode or means of heating water, and the mode or means of supporting the top or hot plate.

With regard to the two functions first above named there are, as ranges are now made, two sorts or modes of construction, arising from the fact that the requirements for the proper performance of either of said functions are exactly the reverse of those best adapted to the other. Thus the range best adapted to roasting and broiling before the fire has an open grate with the fire, as it were, all front, and the back, made or lined with fire-brick or the like, slopes forward toward toward the bottom, so as to reduce the space or area through which the air enters the fire from below. This construction consumes the more fuel on account of the required large exposed fire-surface in front; but in the range best adapted to baking and other operations carried on within the grate has a closed front. The fire required is smaller and farther back toward the center of the range, so that the heat may readily be distributed around and over the ovens and water-heater. The latter construction, having no large exposed fire-surface in front, is altogether the more economical of fuel, (for the fire may be small, comparatively, and yet for the last-named purposes entirely efficient,) and therefore, except

for broiling, &c., before the fire, almost always receives the preference.

Now, the object of the first part of my invention is to produce a range that is perfectly adapted to both the above opposite requirements, thus combining advantages heretofore only obtained from two or more sorts of construction in one and the same range. To this end I construct the grate B of a circular form, or, in other words, like a short cylinder set vertically in the range, and so that a part crops out from the front. One side (or the front) of the grate is made as usual; but the other side (or back) is closed and protected with a thick lining of fire-brick, 4—it may be to the extent of, say, one fifth or fourth the area of the grate—sloping forward toward the bottom, corresponding generally with the construction above described as best adapted to roasting, broiling, &c., before the fire. Said grate or fire-pot has a projecting flange or rim, d, at the top, which rim rests on a ledge, e, of an annular or other proper form surrounding the fire-pot. When, therefore, the range is not required, especially for roasting, but rather for baking, the operator may reverse the position of the fire-pot by turning the same half around horizontally. This effectually closes up the front, and at the same time carries the fire farther back toward the rear. The fire may now be diminished, as before stated, and thus is provided the sort of construction and requirements, hereinbefore alluded to, as best adapted to the operations of baking, heating water, &c., and as most economical of fuel. The first position of the grate (front open) is seen in Figs. 1 and 2. The second or reverse position is shown in Figs. 4 and 5.

The mode of turning the grate is not material to this invention. It may be done by an instrument in the hand of the operator acting on studs on the grate, or it may be turned by a crank on the outside of the range communicating with the grate by any mechanical means with which those versed in the art are familiar.

The second part of my invention concerns the remaining two functions first above enumerated—viz., heating water and supporting the top or hot plate; and this relates principally to the class of larger ranges used by hotels, restaurants, and steamboats, but is applicable to ranges in general which use a water-heater.

In most ranges, especially the larger ones, (many of which use no pot-holes,) the top A (see drawings) is often heated to a red and even a white heat, and therefore requires artificial support in order to sustain the weight of culinary utensils placed thereon. At present there may be said to be two principal modes of providing this support. In one mode it is accomplished from without the range. A rod is attached to a part of the top and fixed to some device above. The other mode consists in the use of channels cast with and forming part of the top, and otherwise arranged so as to have water circulating in the said top or hot plate. The first of these modes is very objectionable by reason of its incumbrance of the top, so as to interfere with the culinary operations, and the second has this objection—viz., that the stratum of water which is introduced into the top or hot plate, by preventing the same from acquiring a high degree of heat, necessarily renders unavailable, to a greater or less extent, that very part of the top or hot plate which, under other circumstances, is, as such, the most efficient.

My present invention is designed to afford a perfect support to the top or hot plate by means which leave the entire under side of said top exposed to the heat beneath, and the whole upper side thereof unobstructed and everywhere available as a hot plate for cooking purposes, as usual, and my said invention therefore consists in providing an independent support, consisting of a cross bar, c. Such cross-bar is arranged beneath the top or hot plate, A, immediately over the fire, and usually in such a position as to leave a clear space between it and the hot plate (seen in Fig. 3) for the play of the heat, and it may or

may not extend entirely across. Upon said cross-bar I have one or more small studs or projections, 1, reaching up to the top A and sustaining the same. To protect this cross-bar from the action of the heat, which otherwise would destroy it in a very short time, I make it hollow, with or without a partition, 7, at the back end, where I fix in two pipes, 2 3, for the reception and discharge of water, so as to cause a circulation of water in said cross-bar. Thus it also becomes a competent means of heating water, and renders the use of a water-back unnecessary. In making this independent support for the top or hot plate, I do not confine myself to form. For example, the cross-bar may have such form that its transverse section would be round, O, or oval, O, or three-sided, Δ . It could be placed nearer the fire or farther from it. Nor do I confine myself to the precise detail of construction herein specified of the grate hereinbefore described, so long as the same is made and operated substantially as set forth.

What I claim as my invention, and desire to secure by Letters Patent, is—

1. The combination, with a cooking-range, of a reversible grate, constructed and operated substantially as and for the purposes specified.
2. The employment of an independent support for the top or hot plate, consisting of the cross-bar or its equivalent, as described, when constructed essentially as set forth, and protected by a circulation of water within, substantially as and for the purposes specified.

ROYAL E. DEANE.
